UNITED STATES PATENT OFFICE.

MAX RICHTER, OF WYOMISSING, PENNSYLVANIA, ASSIGNOR TO TEXTILE MACHINE WORKS, OF WYOMISSING, PENNSYLVANIA, A CORPORATION OF PENNSYLVANIA.

CAM-SHAFT SHIFT-CONTROL MECHANISM FOR FULL-FASHIONED KNITTING MACHINES.

Application filed May 24, 1927. Serial No. 193,828.

My invention relates to full fashioned knitting machines, and more particularly to momentum-absorbing shift-stop mechanism for the longitudinally movable rotary cam shaft thereof, my main objects being to avoid the harmful hammer-blow shocks of such shifting shaft by gradually and progressively absorbing its moving momentum as it approaches the end of its shift in either direction, and to actuate such shock absorbing mechanism from the moving shaft itself.

With these main objects in view, and with others that will appear later as the description proceeds, my invention consists in the improved construction hereinafter fully described in connection with the accompanying drawings forming part thereof, the novel features thereof being pointed out in the subjoined claims.

In the drawings,—

Fig. 1 indicates, in plan view, a portion of the commonly employed longitudinally shiftable and rotary main cam shaft of a full fashioned knitting machine, having applied thereto a preferred embodiment of my novel momentum-absorbing shift-stop mechanism, parts of the latter being broken away to more clearly show its construction.

Fig. 2 is a corresponding side elevation of the same, partly in cross-section on the line 2—2 of Fig. 1.

Fig. 3 is a corresponding transverse sectional view taken on the line 3—3 of Fig. 1.

Fig. 4 indicates a modification of my invention.

The full fashioned knitting machine above mentioned, to which my invention is particularly applicable, is of the well-known Cotton type, and in the accompanying drawings, 5 represents the longitudinally shiftable and rotary main cam shaft commonly employed in all such machines; and 6 the rear longitudinal frame beam also forming part of such known machines, this limited showing, to those skilled in the art, being sufficient to fully disclose the nature of my invention and its manner of operation as hereinafter fully described.

Such main cam shaft 5 commonly extends the entire length of the machine and is necessarily of heavy construction to withstand the severe strains placed upon it; and the large number of cams carried by said

shaft are ordinarily so arranged that by 55 longitudinally shifting the shaft, one set of cams is rendered idle or non-effective, while another set is brought into action as required for determined machine operations. And the longitudinal shifting of 60 the shaft 5 is ordinarily effected as heretofore and in well known manner by pattern control mechanism acting at proper times as required; and due to the heavy construction of the shaft and its cams, 65 and the necessarily relatively quick shifting movements thereof, considerable momentum is developed by said moving shaft, causing 70 harmful hammer-blow shocks at each shift in either direction, also concurrent rebound strains. My improvements are adapted particularly to avoiding such harmful shocks and rebound strains by gradually and progressively absorbing such moving shaft momentum by means of a braking mechanism, 75 so that at the end of its shift in either direction, said shaft may gently come to rest, thus reducing the noise of machine operation and prolonging the life of the machine by eliminating such shocks. My preferred embodiment shown in the drawings will now be described in detail.

Upon the rear frame beam 6, as shown in the drawings, is fixedly secured by bolts 7 and 8, a bed plate member 9, adapted to freely support and carry an expandable clutch ring member 10 which, as shown, is parted to receive an expanding cam 11. A cooperating rotatable brake band member 12, preferably, as shown, in the shape of a cupped cover for said ring 10, rests upon said bed plate 9 and is axially pivoted thereto by a bolt 13 having a bearing in a central hub 14 of said cover member 12. It will be readily seen that the brake band cover member 12 may freely rotate on its axial pivot bolt 13, except as clutch ring 10 is expanded by rotation of cam 11 to cause frictional ring engagement therewith, said ring 10 being held against rotation by its operating cam 11.

To utilize this rotatable brake band member 12 in controlling the shifting movement of cam shaft 5, I preferably employ, as shown in the drawings, a lever 15, centrally pivoted at 16 to a bearing lug 17 indicated as an integrally formed part of bed plate 9; one end of said lever being pivotally con-

ected by a link 18 to a forked projection 19 of member 12, and its opposite end having a bearing block, as shown, engaging between the spaced flanges 20, 20 of a sleeve 21 fixed to cam shaft 5. As cam shaft 5 is shifted in either direction, it will swing lever 15 on its pivot 16 to rotate member 12 in one or another direction. And by determinedly operating expanding cam 11 to cause a gradual or progressively increasing frictional contact of ring 10 with member 12, a regulated momentum-absorbing braking action is imparted to cam shaft 5, whereby the hammer-blow shocks heretofore inherent in shifting said shaft are entirely eliminated.

In order to nicely control and properly time such braking action imparted through cam 11, I preferably employ the rotary action of said shaft 5, as shown, through a double cam 23, 24 mounted on said shaft, cam 23 acting during shifting movement of the shaft in one direction, and cam 24 acting in the reverse shifting movement. In either case one or other of said cams 23 or 24 acts on a bell-crank lever 25, as shown, through an anti-friction roller 26 adjustably secured to the end of one arm 27 thereof, so as to swing said bell crank 25 on its pivot pin 28, the latter carried in a bearing lug 29 shown as formed integrally with bed plate 9; while the opposite end 30 of said bell crank 25 is shown as pivotally connected by a link 31 to a crank arm 32. Crank arm 32 is shown as adjustably fixed to the end of the outwardly projecting shaft extension 33 of cam 11, such shaft extension 33 having an intermediate bearing in bed plate lug 34 so as to rotatably position said cam 11.

It will be readily understood that by properly shaping the periphery of cams 23 and 24 in the construction above described, a very nicely timed and regulated progressive frictional braking action may be imparted to brake band member 12 and through lever 15 to the shifting shaft so that the moving momentum of the latter may be determinedly absorbed during such shaft shift to entirely eliminate any hammer-blow shock of said shifting shaft as it comes to rest at either end of its longitudinal movement, and also the strains of any rebound tendency. And I further so shape said cam peripheries, preferably, that at the end of the cam shift, lever 25 will act to free the frictional grip of ring 10, in order that at the initial moment of the next cam shaft, band brake member 12 and its lever 15 may be free to move without retarding action on the shaft 5; such momentum-absorbing braking action only developing as the shaft shift progresses. Spring 35 shown in the drawings is connected to a fixed part of the machine and acts merely to retain roller 26 in contact with cams 23, 24.

Having thus fully described the nature of my invention and the manner of its operation, I do not desire to limit myself to the specific showing set forth in Figs. 1, 2 and 3 of the drawings, as modifications thereof within the scope of said invention may be readily devised. For instance in Fig. 4 I have indicated one modification that utilizes the shifting movement of the shaft through a single lever 40 to both control the shaft shift and actuate the expanding clutch ring member 10^a. In this construction link 18^a is provided with a slot so that lever 40 may have a limited idle movement before acting to rotate member 12^a; and during such idle movement lever 40, through its projected extension 41 pivotally connected to link 31^a, acts to initially rotate cam 11^a to free said member 12^a from the frictional grip of ring 10^a so that said member 12^a may initially be free to rotate as acted upon by further movement of lever 40. This construction will act in either direction of the shaft shift as in the preferred construction. Other modifications and changes may be devised, all within the scope of my invention, as defined particularly in the following claims.

What I claim as my invention, and desire to secure by Letters Patent, is:

1. In a full fashioned knitting machine, a longitudinally shiftable cam shaft having fixed thereto a lever-engaging sleeve and a lever-engaging cam respectively operative by longitudinal and rotary movement of the shaft, in combination with a momentum-absorbing shift-stop mechanism comprising a movable brake band having a connected lever operated by longitudinal movement of said shaft sleeve, a non-rotatively mounted expansible clutch ring frictionally engageable with said brake band, and ring-expanding means having a controlling lever simultaneously operated by rotary movement of said shaft cam.

2. In a full fashioned knitting machine, a longitudinally shiftable cam shaft having fixed thereto a lever-engaging sleeve and a lever-engaging cam respectively operative by longitudinal and rotary movement of the shaft, in combination with a momentum-absorbing shift-stop mechanism comprising a movable brake band having a connected lever operated by longitudinal movement of said shaft sleeve, a non-rotatively mounted expansible clutch ring frictionally engageable with said brake band, and ring-expanding means having a controlling lever simultaneously operated by rotary movement of said shaft cam; said longitudinal movement of the shaft being positively limited, and said ring-expanding means being adjustable so as to provide determined momentum-absorbing frictional resistance to said longitudinal movement.

3. In a full fashioned knitting machine having a longitudinally shiftable rotary cam shaft, a momentum-absorbing shift-stop mechanism therefor comprising a movable brake band, an expansible brake ring, and means for simultaneously operating said band and ring from the shifting shaft. 35
4. In a full fashioned knitting machine having a longitudinally shiftable rotary cam shaft, a momentum-absorbing shift-stop mechanism therefor comprising braking means, and actuating means for the latter operative from the shaft to produce braking action as the shifting movement progresses. 40
5. In a full fashioned knitting machine having a longitudinally shiftable rotary cam shaft, a momentum-absorbing shift-stop mechanism therefor comprising braking means, and actuating means for the latter operative from the shaft to produce braking action as the shifting movement progresses in either direction. 45
- 20 6. In a full fashioned knitting machine having a longitudinally shiftable rotary cam shaft, a momentum-absorbing shift-stop mechanism therefor comprising braking means, and actuating means for the latter operative from the shaft to produce braking action as the shifting movement progresses in either direction. 50
- 25 7. In a full fashioned knitting machine having a longitudinally shiftable rotary cam shaft, a momentum-absorbing shift-stop mechanism therefor comprising braking means, and actuating means for the latter operative from the shaft to produce increasing braking action as the shifting movement progresses. 55
- 30 8. In a full fashioned knitting machine having a longitudinally shiftable rotary cam shaft, a momentum-absorbing shift-stop mechanism therefor comprising shaft actuated braking means operative during shifting movement of said shaft. 60
9. In a full fashioned knitting machine having a longitudinally shiftable rotary cam shaft, a momentum-absorbing shift-stop mechanism therefor comprising shaft actuated braking means operative during shifting movement in either direction of said shaft. 65
10. In a full fashioned knitting machine having a longitudinally shiftable rotary cam shaft, a momentum-absorbing shift-stop mechanism for said shaft operated by the latter to control its longitudinal shift. 70
11. In a full fashioned knitting machine having a longitudinally shiftable rotary cam shaft, a momentum-absorbing shift-stop mechanism for said shaft operated by the latter with progressively increasing force during its shifting movement to determinedly control such movement. 75

In testimony whereof I affix my signature.
MAX RICHTER.
